UNITED STATES PATENT OFFICE.

ERNEST DUSCHER, OF LA CROSSE, WISCONSIN, ASSIGNOR, BY MESNE ASSIGNMENTS, TO PRINTOGRAPH MANUFACTURING CO., OF ST. PAUL, MINNESOTA, A CORPORATION OF SOUTH DAKOTA.

FILLING-IN ATTACHMENT FOR PRINTING-MACHINES.

1,221,159.

Specification of Letters Patent.

Patented Apr. 3, 1917.

Application filed November 15, 1911. Serial No. 660,425.

To all whom it may concern:

Be it known that I, ERNEST DUSCHER, a citizen of the United States, residing at La Crosse, in the county of La Crosse and State 5 of Wisconsin, have invented a new and useful Improvement in Filling-In Attachments for Printing-Machines, of which the following is a specification.

My invention relates to improvements in 10 printing machines and its object is to provide a type bed which may be introduced on the main type bed of the machine in connection with type forms thereon, to carry a supplementary form exchangeable and adjustable with relation to the other forms carried by the machine.

In connection with this main object my device is adapted to the insertion and removal 20 of supplementary type forms such as are used in printing different salutations on copied letters and in printing the addresses on envelopes, and to the automatic regulation of the ribbon during the changing of the forms.

25 Further objects will be apparent from the following description.

My device is simple in construction and accurate in operation, the particular form shown being especially adapted but not 30 necessarily confined to use in connection with a printing machine such as described in applicant's companion application Serial No. 652,105, filed Sept. 30, 1911, for printing machines and improvements thereon.

35 In the drawings with which I have illustrated my invention and which form part of this specification, Figure 1 is a plan view of a printing machine of the class mentioned equipped with my improvement; Fig. 2 is a view on the line X—X, Fig. 1 showing a side 40 elevation of my improvement; Fig. 3 is a section on the line Y—Y, Fig. 1 showing the action of the ribbon lifter; Fig. 4 is a plan view of my improvement; Fig. 5 is a side 45 elevation of my improvement, part in section; Fig. 6 is an enlarged detail of a portion of Fig. 5 in a different position of the parts; Fig. 7 is a perspective of the supporting bracket used in connection with my im- 50 provement; Fig. 8 is a perspective of the supplementary type form used in connection with my device; Fig. 9 is a section of a detail illustrating the supplementary type

form mounted in printing position on the printing block, and Fig. 10 is a detail in section showing a portion of the type form and one of its type.

In the above drawings I have shown a printing machine having a supporting frame, a type bed B carried by the frame A, 60 on which a form C may be supported, and with which a traveling platen D coöperates in making a printing impression. My supplementary type bed or printing block E is shown mounted on the type bed B and carrying a supplementary type form, type holder or name plate F which is so positioned by the printing block E as to coöperate with the platen D in the same manner as the form C on the bed B.

On the frame A are mounted sprocket wheels 2 carrying sprocket chains 3 at each side of the machine on which is mounted the platen D in the form of a roller which traverses the type form and having a wear 75 wheel 5 at each end through which printing pressure is imparted to the platen. The type bed B is so positioned with relation to the path of the platen D carried by the sprocket chains 3 that the platen normally 80 travels orbitally about the type bed, and above the surface of the type in the form and out of contact with it.

Printing pressure on the platen is secured by means of pressure bars 6 at each side of the machine under pressure from the spring 85 7 which may be adjusted to different degrees of pressure. The under surface of the pressure bar 6 is formed with rectangular notches 8 which bear upon a portion of the periphery of the wear wheels 5 producing an intermittent pressure and repeated impacts on the platen and thereby on the form.

A tabulating rail 9 is shown at each side 95 of the machine on which travels the wear wheel 5. The upper surface of the tabulating rail is formed with a steel ribbon 10 resiliently mounted on it by means of which local adjustments of pressure on the form may be secured.

A color inking ribbon 11 is mounted on the machine between the path of the platen and the type form and is carried over suitable rollers 12 connected by gears 14 with the sprockets 2 to be operated. An operating handle 15 connected with one pair of 105

sprockets 2 operates the platen D and the ribbon 11 in the usual manner, that is the ribbon is stepped across the bed or type form at suitable intervals while the handle is turning, the ribbon remaining stationary while each impression is being made. The specific construction for accomplishing this result is not shown, any form being adapted for use with my invention and not constituting part thereof. Two forms for accomplishing this result are illustrated and described in Patent No. 1,944,094, issued to William A. Sorg on the 12th day of November, 1912, and in my application for patent, Serial No. 681,382, filed on March 4, 1912.

My supplementary type bed or printing block E consists of a body part 16 of comparatively narrow width and extending transversely across the type bed and parallel with the line of motion of the platen D. The body 16 rests directly on the type bed B on which it is adjustable vertically by means of set screws 17, this adjustment being permanent when once made, to bring the printing surface 18 to such an elevation that standard type 19 in the supplementary type form F have an equal elevation with the type commonly used in the form C on the bed B.

The printing surface 18 as commonly used for addresses or salutations extends less than the width of the type bed B, and at both ends of the face 18 the body 16 is cut away or depressed in elevation so that the type in the form F when resting on or above these parts of the body 16 do not have printing contact with the ribbon 11 during the passage of the platen D.

The sides of the body 16 are formed with grooves 20 extending the full length thereof for the engagement of the name plate F which is formed with lugs 21 adapted to travel in the grooves 20 during the longitudinal movement of the plate F along the printing block. The lugs 21 extend down the sides of the printing block and into the grooves 20 and allow the type 19 carried by the name plate to rest upon the printing surface 18 when the name plate has reached that part of the block. A spring 22 is fixed on one side of the block E by means of a screw 23. The spring has contact tips 24 and 25 adapted to lie between the lugs 21 on one side of the name plate F when the name plate is in printing position on the printing surface 18. The spring tip 24 has a beveled surface adapted to permit the movement of the name plate toward the tip 25 while the tip 25 is seated in a notch 26 in the block and presents an abrupt face preventing the return movement of the name plate when once engaged by it. As the name plate is moved along the block E the front lug 21 of the plate engages the spring 24 and passes under it and moves on opening up the tip 25

by pressure from inside. When the tip 24 engages the rear lug 21 of the plate its pressure is instantly felt by the operator as well as the release of the tip 25 which at the same instant drops behind the forward lug 21. The movement of the plate is thus stopped and for the purpose of printing it is firmly held on the block but it may be advanced by the operator and moved off the block in the same direction in which it was moved onto the block.

An extension 27 having the same width as the block E is connected with the block by means of screws 28 and extends beyond the machine permitting a plate F to be pushed from the block and from under the color ribbon 11. The movement of the plates F along the block is accomplished by means of a pusher 29 which slides in a slot in the block on a rod 30 which is mounted on the block. A spiral compression spring 31 is mounted on the rod 30 in front of the pusher 29 and is compressed by it during the forward movement of the pusher in advancing the plate and upon the release of the pusher returns it sharply and automatically to its original position. The pusher 29 is formed flush with the depressed surface of the approach of the printing block and is adapted to be operated by hand such as by the finger or thumb of the printer. In order to secure the engagement of the end of the name plate F by the pusher a spring stop 32 is mounted in the pusher, normally lying flush with the upper surface of the pusher. The lower extremity of the stop 32 in the normal position of the pusher lies in a recess 33 in the rod 30 and is held in that position by a spring 34 mounted on the stop.

The recess 33 is short and when the pusher is advanced to engage a plate the end of the stop 32 is forced upward to the level of the normal surface of the rod 30 thus forcing its upper extremity above the level of the pusher as illustrated in Fig. 6 where it is adapted to engage the edge of a plate F and advance it during the further movement of the pusher.

As soon as the pusher has returned to the position shown in Fig. 4 the stop 32 is retracted by the action of the spring 34 and the paper is free to travel out of the machine without obstruction.

To prevent the interference of the plates F and the ribbon 11 during their advancement along the block E the ribbon is automatically held out of contact with the plate by means of a spring 35 positioned longitudinally of the block E and near the side of the ribbon adjacent to the approach of the block. This spring stands above the level of the type in the plate and normally keeps the ribbon raised therefrom. It is however a comparative weak spring permitting the platen to bring the ribbon into con-

tact with the type without resistance, and is formed of smooth wire to permit the unobstructed travel of the ribbon.

The body 16 of the block E rests upon the bed B, the approach extremity of the block is in contact with the bar 37 of a supporting bracket 38 which is mounted on the type bed B being fixed adjustably to the edge of the type bed by means of tap screws 39 and set screws 40 which are adapted to adjust the elevation of the bar 37 to any desired point. The bracket is formed with an angle shaped part 41 embracing the corner of the type bed B and the longitudinal movement of the block E is prevented by lugs 42 and 43 lying transversely on the under surface of the block which engage the upper leg of the angle part 41.

In operating my device it is positioned on the type bed at the same time that the form C is placed thereon and is fixed laterally with relation to the ends of the type bed (by spacing blocks) in the usual manner. The ribbon is placed above it in printing position resting on the spring 35. The first name plate is then placed on the printing block E and after proper adjustment of the form C and pressure bars 6 paper is placed on the ribbon and the platen is operated in the usual manner producing a printed impression from both the form C and the plate F at the same time.

When it is desired to change the name plate F a new one is placed on the approach of the printing block and the pusher 29 is advanced moving the plate F forward on the block. The first used plate F is forced off the printing surface 18 along the block toward the extension 27 from which it may be removed by hand.

The replacing of the plates F on the block may be accomplished without interrupting the operation of the printing machine between the passages of the platen over the form. For convenience in positioning sheets or envelopes on the type forms paper guides 45 and 46 of different lengths may be mounted on the machine said guides 45 also acting as lifters for the paper. Stripers 47 may also be used to engage the lifted sheets and envelopes and remove them from the machine. Paper slides 48 are mounted on the bar 37 to deliver printed sheets from the machine. These guides, strippers and slides will be found fully described in my companion application above referred to.

The name plate or supplementary type form F has the form of a plate with a series of slots 50 in which are mounted suitable double shouldered type 19 adapted to engage the side of the slots for support to prevent lateral movement of the type when in printing position and to hold the type assembled when not being used in the machine. Each of two opposite sides of a

type has two shoulders 51. The type 19 are placed in the slots 50 in suitable form for printing salutations, addresses and the like and are locked in the slots by compressing the shoulders of the type at the end of the series or of a suitable blank similarly located, into engagement with the sides of the slot 50. The grooves between the shoulders 51 of the type on each of two opposite sides of the type in which the sides of the slots 50 in the name plate engage are of sufficient width to enable each type to engage the name plate freely and to rest on the raised surface of the block without being supported by the name plate during printing.

The end portions of the plate are depressed below the level of the type bearing slots which are open at one end to receive type. The end portions of the plate described have depending lugs 21 formed integral with the plate at each corner of the plate for engagement with the grooves in the sides of the printing block as described.

The manner in which the type are fastened to the name plate so that they can move up and down between their shoulders 51 permits the type to stand in printing position, vertically independent of said plate as illustrated in Fig. 9, with their lower ends resting on the raised portion 18 of the block and in non printing position as illustrated in Fig. 10 before and after the plate is positioned on said raised portion.

It is evident that my printing block may be used in the present or modified form in connection with any machine of the class described in which a type bed, an inking ribbon, and a traveling platen coöperate. It is also evident that for different purposes the length of the printing surface on the block may be increased with relation to the type bed and that if desired a series of printing blocks similar to that described or of any suitable construction may be used in making up a form having variable parts.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:

1. In a printing machine having a type bed, a platen movable across said bed and an inking ribbon between said parts, a supplementary type bed arranged across said main bed, a type holding plate adapted to be engaged by said supplementary type bed

and to be guided into printing position and type held by said plate and having free vertical play whereby the type are adapted to stand in printing position on their lower ends upon said supplementary bed vertically independent of said plate.

2. In a printing machine, a supplementary type bed, a holder for type horizontally movable into and out of printing position upon said bed, said bed having a raised portion adapted to coact with a type in said holder to support it in printing position, and a lower portion adapted to permit the type to rest in non-printing position when off of said raised portion and means for automatically engaging said holder tending to prevent longitudinal movement thereof while resting over said raised position.

3. In a printing machine, a type bed adapted to support a changeable type form, means permanently attached to said bed for adjusting it in height upon a support, and means arranged adjacent said bed adapted to raise an ink ribbon clear of said type form, while the latter is being changed, for the purposes specified.

4. In a printing machine, a type bed adapted to support a changeable type form having inturned engaging hooks projecting down from its side edges, said bed having a receiving portion, an engaging portion adjacent said receiving portion adapted to receive said hooks as said form is advanced on said bed, and a raised surface portion on said engaging portion, a longitudinal guide carried by said bed below its surface, a plunger movable upon said guide and adapted to engage and advance a plate on said bed from said receiving portion toward said raised surface portion, and a spring adapted to retract said plunger into position to receive a new form.

5. In a printing machine, an auxiliary type bed, having a raised surface, a changeable type form adapted to slide into printing position on said raised surface, and a spring arm carried by said type bed, whose tendency is to move upwardly above said raised surface and automatically raise a ribbon above the plane of the printing surface of type on said raised surface, said arm being depressible to permit the ribbon impinging against the printing surface of said type.

6. In a printing machine, a supplementary type bed having a raised surface, a holder for type engaged by said bed and movable into and out of printing position upon said raised surface, said raised surface being adapted to co-act with the type in said holder to support them in printing

position, and said type being supported freely in said holder permitting vertical play, whereby said type are held in non printing position before and after a holder moves respectively into and out of co-operation with said raised surface, and means for placing a type holder on the raised surface of said bed to produce a co-operation between the type therein and said raised surface and for removing said holder after said co-operation.

7. In a printing machine, a supplementary type bed having a raised surface portion, a holder for type engaged by said bed and movable into and out of printing position upon said raised portion of said bed, said raised portion adapted to coact with the type in said holder to support them in printing position and said type being supported freely in said holder permitting vertical play, whereby said type are held in non-printing position before and after a holder moves out of co-operation with said raised portion.

8. In a printing machine, a supplementary type bed, a holder for type engaged by and adapted to slide upon said bed into and out of printing position, said bed having a raised portion adapted to coact with type in said holder to support them in a plane to print and all of said type being movably held by said holder to recede, whereby they are all adapted to be supported in non-printing position by said bed below said plane except when coöperating with said raised portion.

9. In a printing machine, a supplementary type bed, a holder for type engaged by and adapted to slide upon said bed into and out of printing position, said bed having a raised portion adapted to co-act with type in said holder to support them in a plane to print and all of said type being movably held by said holder to recede, whereby they are all adapted to be supported in non printing position by said bed below said plane, except when coöperating with said raised portion, a push piece movable longitudinally in said type bed having means for engaging a holder to move the latter forwardly upon said bed and means for automatically returning said push piece out of engagement with said holder.

In testimony whereof, I have signed my name to this specification, in the presence of two subscribing witnesses.

ERNEST DUSCHER.
